UNITED STATES PATENT OFFICE.

HARRY J. POTTER, OF NEWTON, MASSACHUSETTS, ASSIGNOR TO DENNISON MANUFACTURING COMPANY, OF BOSTON, MASSACHUSETTS, A CORPORATION OF MASSACHUSETTS.

ATTACHING DEVICE.

1,027,431.

Specification of Letters Patent.

Patented May 28, 1912.

Application filed February 21, 1911. Serial No. 610,018.

To all whom it may concern:

Be it known that I, HARRY J. POTTER, a citizen of the United States, residing at Newton, in the county of Middlesex and 5 State of Massachusetts, have invented a new and useful Attaching Device, of which the following is a specification.

The requirements with respect to devices for attaching tags to such objects as bales 10 of cotton and other material are exceptionally severe. They must possess the capability of being quickly and securely applied to the bale by a person neither intelligent nor 15 deft; and they must resist accidental displacement under rough handling and removal by the meddlesome or malicious, yet when desired must be readily detachable by those authorized. It is further important that the face of the tag shall be held outwardly close to the bale, or in a plane substantially parallel thereto. The device hereinafter described and claimed effectually 20 attains all these objects, and is, moreover, very simple, preferably consisting of one integral 25 piece of wire bent to the proper form, and may therefore be cheaply manufactured.

One embodiment of my attaching device is illustrated in the accompanying drawings, in which—

30 Figure 1 is a front elevation; Fig. 2 is a side elevation; Fig. 3 an end view; Fig. 4 shows the device during the act of applying it to a bale, it being at the forward extreme of its engaging thrust; 35 Fig. 5 illustrates it drawn back into final engagement; Fig. 6 shows a position of the device during detachment; and Fig. 7 shows a tag in place upon a bale.

In all figures of the drawings like characters are applied to similar elements.

As indicated, my improved tag-fastener A consists of a single piece of wire bent at a into a general U-form; that is, having two adjacent arms b and c extending from their 45 curved juncture. The arm b terminates in a sharpened engaging or entering projection 10; while the associated arm c at some distance inwardly from the extremity of b first diverges from the latter at 11, and is 50 then bent approximately at right angles at 12 and curved about b at 13, embracing it through an arc, which, as illustrated, is about 180°. Near the end this arc comes 55 into yieldable contact at 13a with the entering member, they being forced toward one

another by the spring of the arms. This curved portion furnishes a stop-shoulder and fulcrum, as will hereinafter more clearly appear. At 14 the member c is again bent so that it extends in a sharpened engaging 60 or locking projection 15 which diverges from the member or arm b, and also rearwardly from the plane of the two shank portions of the arms, it extending across the same at an acute angle to both shank portions, 65 with its point at the opposite side from the angle 12.

When the arms b and c are freed from engagement with one another, and sprung apart at their outer or entering and locking 70 extremities, a tag may be slipped over the former. A type of tag adapted for use with this device is one such as is illustrated at B, having two eyelets, one, d, being near the center of one end, while the other, e, is at an 75 appropriate distance therefrom along an axial line.

Adjacent to the juncture a the arm b is provided with a bent portion or recess 15a, equal in length to the distance between the 80 tag-eyelets and extending away from the arm c. Opposite this recess the arm c has two lateral projections 16, 16, conveniently formed by bending the wire into opposite arcs of circles, these lying approximately 85 in a plane at right angles to that of the shanks. The extremity 10 of the arm b is first inserted in the eyelet e from the front side of the tag and then from the rear through eyelet d, and said tag drawn down 90 until the portion between the eyelets rests in the recess, it being thereby permitted to lie unbent and is retained against return movement along the shank. The tag also tends to remain in substantially the same 95 plane, so that upon attachment to an object its face will always be visible, since the projections 16, 16 contact with it if it rocks about the arm b in either direction and limit such displacement.

100 In applying the tag to a bale the device A is grasped near the juncture of the arms, the thumb of the user conveniently resting upon the broadened portion furnished by the projections 16, which thus add to their other functions that of a finger-hold, and also give rigidity to the device, which is an important feature, in that it furnishes resistance to the stress applied by the user. The extremity 10 is then thrust into the bale 110

22

upwardly and nearly parallel to the surface, until the point of the locking projection 15 is in the proper position to engage the fabric, as appears in Fig. 4. Then the junction 5 of the arms, or tag-retaining portion, may be pressed toward the bale and the device drawn back. This causes the projection 15 to enter until the shoulder 13 is reached, the angle of the projection 15 forcing the fabric by the point 14 onto this shoulder (see Fig. 5). The device is now held by the shoulder and by the spring engagement of the arms at 13 against longitudinal movement in either direction. The 10 points 12 and 14 rest against the face of the bale and prevent the fastener from turning axially, and this, combined with the peculiar construction of the tag-retaining portion, holds the face of the tag parallel with 15 the surface of the bale, where the inscription may be easily read. Since both engaging projections are entirely concealed behind the fabric, one unacquainted with the device will find difficulty in removing it, yet the 20 informed user, without special effort or skill, seizing the holding or finger portion has only to turn the device right-handedly about its axis until the fabric clears the stop-shoulder and then press upwardly until 25 the locking projection is free. A further rotation of the device upon the angle 12 as a fulcrum (Fig. 6) springs the arms from one another and raises the locking projection above the fabric when a pull with- 30 draws the entering projection and releases 35 the entire device.

I claim:

1. An attaching device comprising connected members lying first substantially parallel to one another, one of said members being provided with an entering point, and the other member being curved about its companion member in a plane substantially at right angles thereto and then extending in the opposite direction from the 40 entering point, crossing the parallel portions of the members and diverging rearwardly from the plane of said members, it terminating in a locking point.

2. An attaching device comprising connected members lying first substantially parallel to one another and furnishing tag-holding means, one of said members being provided with an entering point, and the other member diverging from its companion and then being curved about the same, the curved portion and the juncture of the diverging and curved portions giving, respectively, a stop-shoulder and a releasing fulcrum, the curved member beyond the 55 stop shoulder extending in a direction opposite to the entering point and crossing the parallel portions of the members and diverging rearwardly from the plane of said members, it terminating in a locking point.

60 Signed at South Framingham, in the county of Middlesex and State of Massachusetts, this 6th day of February, 1911.

65 HARRY J. POTTER.
